FUEL INJECTION NOZZLE ASSEMBLY

Frank De Luca, Thompsonville, Conn., assignor to American Bosch Arma Corporation, Springfield, Mass., a corporation of New York

Filed Apr. 26, 1966, Ser. No. 545,290

9 Claims. (Cl. 123—32)

ABSTRACT OF THE DISCLOSURE

In combination with an engine having an engine cylinder head and at least one combustion chamber, an air intake passage to the valve controlled intake port of the combustion chamber and an elongated bore opening into the combustion chamber for mounting therein a fuel injection nozzle assembly. The fuel injection nozzle assembly includes a nozzle having a tip adapted to direct fuel into the combustion chamber and a holder adapted to be connected to a fuel supply to deliver fuel to the nozzle tip. The assembly further includes a fuel leak-off chamber to collect normal fuel leakage, passageway means directly connecting the leak-off chamber to the air intake passage, and seal means insuring direct discharge of fuel from the leak-off chamber into the air intake passage.

The present invention relates to a fuel injection nozzle for injecting fluid fuel into the cylinders of internal combustion engines and more particularly to a novel assembly including means for exhausting leakage fuel directly into the air intake chamber of the engine.

As is conventional in some internal combustion engine assemblies, a fuel injection nozzle is provided for each cylinder of the assembly to discharge fuel directly into the engine cylinder. These nozzle assemblies generally comprise an elongated, generally cylindrical nozzle holder having a fuel passageway therein to direct fuel from a suitable source to the nozzle mounted at one end of the holder. The nozzle has an axial bore which mounts therein a valve element which is normally biased to close the spray orifices in the nozzle tip which projects into the engine cylinder by means of a spring housed in the holder. The nozzle further includes an annular fuel chamber and a fuel passage connecting the annular chamber to the fuel passageway in the holder whereby upon fuel pressure build up in the annular chamber, the valve element is raised to permit fuel to be delivered through the orifices in the outer end of the nozzle tip. It has been found that there is a certain amount of fuel leakage which bypasses the valve element and returns to the spring chamber which must be vented for proper operation of the fuel injection nozzle. Accordingly, most of these assemblies include a leakoff channel in the holder communicating with the spring chamber which, through suitable fittings and a line, is connected back to the fuel supply source. In some instances, the leakoff port communicates directly with a fuel leakoff passageway in the holder. It has been found that even if the parts are finished to provide very close tolerances between the movable parts of the fuel injection nozzle, such as the valve and the nozzle bore, nevertheless, there is a certain amount of fuel leakage in the operation of the nozzle and in order for the nozzle to operate properly, this leakage must be vented.

As is readily apparent, the additional piping and fittings required for the fuel leakoff as well as the formation of the leakoff channel in the holder add to the cost of the nozzle assembly. Moreover, the return lines and fittings take up valuable space in an already crowded area of the engine and nozzle assembly.

2

The present invention provides a new and improved leakoff arrangement which eliminates the undesirable features and drawbacks of the prior systems discussed above. In accordance with the present invention, a leakoff port is provided in the cylinder head communicating at one end with an annular chamber defined between the holder and opening in which the nozzle assembly is mounted which receives the leakoff fuel and at its opposite end with the intake port just above the valve seat of the air intake valve.

Still another object of the present invention is to make a more compact fuel injection nozzle assembly by eliminating the axially extending conventional leakoff passageway in the nozzle holder.

These and other objects of the present invention and various features and details of the operation and construction thereof are hereinafter more fully set forth with reference to the accompanying drawings, wherein:

FIG. 1 is a fragmentary sectional view through an engine block showing a fuel injection nozzle and leakage fuel bypass combination in accordance with the present invention;

FIG. 2 is an enlarged fragmentary sectional view through a portion of the fuel injection nozzle;

FIG. 3 is a sectional view taken on lines 3—3 of FIG. 2;

FIGS. 4 and 5 are sectional views similar to FIG. 3 showing other embodiments of a fuel injection nozzle and leakage fuel bypass combination in accordance with the present invention.

Referring now to the drawings, there is illustrated in FIG. 1 a fuel injection nozzle assembly 10 mounted in an elongated bore 11 in an engine cylinder head 12 with the tip portion extending into the piston chamber 14. The engine includes an air intake valve 13 mounted in an air intake chamber or passage 15. The fuel injection nozzle assembly comprises an elongated, generally cylindrical holder 16 and a nozzle 18 mounted on one end of the holder by means of a cap nut 20.

The nozzle, as best illustrated in FIG. 2, comprises an upper generally cylindrically body portion 24 and an elongated nozzle shank 26 extending from the body portion. The fuel nozzle has a stepped axial bore 28 comprising an upper bore section 28a and a lower bore section of smaller size 28b, the juncture of the bore sections being enlarged to define an annular fuel chamber 30. A valve member 32 is mounted in the axial bore having a conical tip 34 which seats on a conical seat 36 at the terminal end of the nozzle tip 26. This valve element 32 is normally biased to a closed position up against the seat 36 by means of a spring 40 housed in the spring chamber 42 in the holder 16, the spring chamber 42 also in the present instance defining a fuel leak-off chamber to collect normal fuel leakage.

Fuel is delivered from a suitable supply source through an inlet 44 at the upper axial end of the holder 16 through an elongated fuel passageway 46 in the holder which communicates at its inner terminal end with a short passage 48 in the nozzle body which in turn, as illustrated in FIG. 2, terminates in the fuel chamber 30. By this arrangement, when fuel pressure builds up in the annular chamber 30 and acts on the tapered shoulder 50 of the valve element 32, and is of a sufficient degree to overcome the force of the spring 40, the valve 32 is raised whereby the fuel passes from the chamber 30 down through the annular space between the valve and the bore section 28b through the orifices 52 in the tip end of the nozzle and into the engine cylinder or combustion chamber.

In the normal operation of the fuel injection nozzle there is a certain amount of leakage between the valve and the bore in which the valve is mounted, and as

noted above, it is necessary to provide venting means for the leakage fuel for proper operation of the fuel injection nozzle. More specifically, the fuel leakage passes between the upper bore section 28a and the valve element into the spring chamber 42. In accordance with the present invention, means is provided for venting the leakage fuel and exhausting it directly to the intake manifold or chamber 15 of the engine. To this end there is provided in the present instance a short radial channel 60 in the holder which communicates at one end with the spring chamber 42 and at its outer terminal end with an annular recess 62 provided by an undercut on the holder between the holder and the wall of the bore 11 in which the nozzle assembly is mounted. This annular recess 62 as best illustrated in FIG. 2 communicates directly with the air intake chamber 15 through a bypass port 70. Sealing means are provided above and below the annular recess 62 so that the leakage fuel is exhausted directly into the air intake manifold 15. The sealing means comprises, as best illustrated in FIG. 1, an annular sealing ring 72 which seats in a groove in the holder above the recess 62 and a sealing disc 74 between the lower face of the cap nut 20 and the annular shoulder at the juncture of the step of the opening 11 in the engine block 12.

By this arrangement, during operation of the valve fuel leakage entering into the spring chamber 42 passes through the radial port 60, annular recess 62, bypass port 70 into the air intake manifold 15. It is noted that in the air intake manifold 15, fuel enters just above the intake valve 13 where the air velocity is relatively high so that the leakage fuel is well aspirated. This aspirated leakage fuel is then drawn into the engine cylinder on the intake stroke whereby some precombustion reactions take place prior to injection of the main fuel charge into the combustion chamber.

Furthermore, this leakoff bypass arrangement is a much simpler arrangement than the previously known methods employing a leakoff channel in the nozzle holder, fittings on the nozzle holder and line directing the leakage fuel back to the main fuel supply. Elimination of these parts greatly simplifies construction and overall cost of the assembly.

There is illustrated in FIGS. 4 and 5 other embodiments of fuel injection nozzle assemblies having leakage fuel venting means in accordance with the present invention. The fuel injection nozzle assembly of FIG. 4 is generally identical to that described above and comprises an elongated generally cylindrical holder 116 and a nozzle 118 mounted at one end of the holder by means of a cap nut 120, the entire assembly being mounted in an elongated bore 111 in an engine cylinder head 112. A valve member 132 is mounted in an axial bore 128 in the nozzle 118 and is normally biased to a closed position by means of a spring actuator 140 mounted in a spring chamber 142 in the lower end of the holder 116. As illustrated, the bore 111 is slightly larger than the cross section of the fuel injection nozzle assembly to provide an annular space 119 which space is sealed at opposite ends by sealing means including an O-ring 172 mounted, in the present instance, in a recessed groove 173 in the wall of the bore 111 and a sealing disc 174. This annular space 119 communicates with a fuel leakage bypass port 170 in the engine cylinder head 112 which discharges into the air intake chamber of the engine. In the present instance the leakage fuel is directed into the bypass port 170 by counterboring the inner end of the upper bore section 128a to provide an annular recess 131 in the inner axial end face of the nozzle body portion 116 which recess 131 communicates with the annular space 119 between the fuel injection nozzle assembly and the bore 111 through a radial slot 133 in the inner axial end face of the nozzle body and drilled hole 135 in the holder. By this arrangement in the operation of the fuel injection nozzle assembly, any leakage fuel bypassing the valve element and upper axial bore section

passes into the annular recess 131 and through the radial slot 133 to the annular space 119 surrounding the assembly and from there into the bypass port 170 and air intake chamber communicating with the port 170.

The fuel injection nozzle assembly of FIG. 5 also includes a holder 216 and a nozzle 218 mounted on one end of the holder by means of a cap nut 220. The bore 211 is engine head 212 in which the fuel injection nozzle assembly is mounted is slightly enlarged to define an annular space 219 which communicates with the air intake chamber through a bypass port 270. The annular space 219 is sealed by an O-ring in a recessed groove in the wall of the bore 211 as in the arrangement of FIG. 4, and a sealing disc 274. The assembly further includes a valve element 232 normally biased to a closed position by means including a biasing spring 240 housed in a spring chamber 242 in the lower axial end of the holder. Leakage fuel is directed to the air intake chamber by means including, in the present instance, a short radial channel 250 in the holder and a short axial connecting leg or channel 252 which connects the short radial channel with the upper end of the spring chamber 242, the channel 250 communicating with the annular space 219.

While particular embodiments of the present invention have been illustrated and described herein, it is not intended to limit the invention and changes and modifications may be made therein within the scope of the following claims.

I claim:

1. In combination with an engine having an engine cylinder head and at least one combustion chamber, an air intake passage to the valve controlled intake port of the engine combustion chamber and an elongated bore opening into the combustion chamber for mounting therein a fuel injection nozzle assembly, the fuel injection nozzle assembly in the bore including a nozzle having a tip adapted to direct fuel into the combustion chamber and a holder adapted to be connected to a fuel supply to deliver fuel to the nozzle tip, said assembly including a fuel leak-off chamber to collect normal fuel leakage, passageway means directly connecting the leak-off chamber to the air intake passage and seal means insuring direct discharge of fuel from the leak-off chamber into the air intake passage.

2. The combination as claimed in claim 1 wherein said fuel injection nozzle assembly comprises an elongated holder and a nozzle mounted at one end of the holder, a valve element mounted in an axial bore in the nozzle, biasing means mounted in a leak-off chamber in the holder for normally urging the valve element to a closed position and wherein said passageway means connects the leak-off chamber to the air intake passage.

3. The combination claimed in claim 2 wherein said passageway means includes means defining an annular recess in the holder, a radial port connecting the leak-off chamber with the annular recess and a channel in the engine cylinder head directly connecting the annular recess to the air intake passage.

4. The combination as claimed in claim 3 wherein the elongated bore in the engine cylinder head is of a larger cross section than the outer diameter of the holder-nozzle assembly to provide an annular space therebetween with which the passageway means communicates.

5. The combination as claimed in claim 4 wherein said seal means is disposed on opposite sides of said annular recess whereby leakage fuel is directed into the connecting channel.

6. The combination as claimed in claim 5 wherein the seal means comprises a sealing ring mounted in a groove in the holder and a sealing disc at the step in the opening in the engine cylinder head against which a cap nut securing the nozzle to the holder abuts.

7. The combination as claimed in claim 2 including an annular recess provided by counterboring said axial bore in the nozzle at the axial end face thereof adjacent

the holder and a slot in said axial end face communicating at one end with said recess and at its opposite end with said passageway means.

8. The combination as claimed in claim 2 including a short radial channel in said holder communicating with said pasageway means and a short axial connecting channel which connects the radial channel with the upper end of the leak-off chamber.

9. The combination as claimed in claim 8 wherein said seal means comprises a sealing ring mounted in a

groove in said bore for said fuel injection nozzle and a sealing disc at the step in the opening in the engine cylinder head against which the cap nut securing the nozzle to the holder abuts.
